UNITED STATES PATENT OFFICE.

HEINRICH HENKEL, OF BRUSSELS, BELGIUM, ASSIGNOR TO FRANZ HABRICH,
OF HAGEN, GERMANY.

SYSTEM OF CONSTRUCTION WITH BETON STRENGTHENED BY METAL.

SPECIFICATION forming part of Letters Patent No. 693,966, dated February 25, 1902.

Application filed May 14, 1901. Serial No. 60,131. (No model.)

To all whom it may concern:

Be it known that I, HEINRICH HENKEL, a citizen of Germany, and a resident of 15 Rue du Gouvernement Provisoire, Brussels, Belgium, have invented a certain new and useful System of Construction with Beton Strengthened by Metal, of which the following is a specification.

The present patent application has for its object a new system of construction with beton strengthened by metal, by which structures of all kinds can be built with as small as possible an amount of material, while insuring great stability. By this method of construction the time required for execution of the work is greatly lessened, as well as the preparatory work required for other systems. The new method is equally applicable to floors, reservoirs, walls, quays, &c.—that is to say, to all kinds of structures.

Figures 1 and 2 of the annexed drawings show by way of example the application of the system to the construction of a floor. Fig. 2^a is a perspective view like Fig. 2 of a different arrangement of the parts; Figs. 3 to 6, the application of the same method to the construction of a gasometer-tank. In the first example the structure is horizontal, while in the second it is cylindrical.

In the case of the floor (shown in Figs. 1, 2, and 2^a) two girders *a* are placed the one some distance above the other and are connected at intervals by clips *b*. The girders are quite buried in beton, forming a beam *fghi*, in which the upper girder is subject to compression and the lower to tension, the neutral axis being between the girders *a* in the mass of beton. The panels *y* are made of thinner beton and may extend over great space, owing to the special arrangement of the strengthening metal *z* of helically-twisted bars of flat iron extending in one piece without a break over three, four, or five panels, passing for this purpose through between the girders *a* in the neutral axis of the beam. Thus the panels between the beams are not separated from each other, as in ordinary structures, but, on the contrary, are intimately connected to one another, so that the floor may be considered to be in one piece.

Furthermore, the irons *zz* pass to and fro several times through the same set of panels, being for this purpose at each of the end beams bent back upon themselves several times, as shown at *l*. On the other hand, the adjacent irons are connected to each other by passing through loops *l*, so formed as to constitute continuous strengthening metal over the whole extent of the floor. (See Fig. 2^a.) This construction of floor presents a great advantage on account of the ease with which it can be executed, as the scaffold-planks can be hooked to the lower girder *a* without requiring other supports.

The application of the system to the construction of reservoirs (shown in Figs. 3 to 6) presents the following specialties: The mode of construction is absolutely the same, comprising, like the former, the combination of sets of double girders and helically-twisted strengthening-bars of flat iron, only the structure is vertical instead of horizontal. As the floor is divided into a number of panels between beams, so the reservoir consists of a set of vertical curved panels between similar vertical supports. The girders *v*, corresponding to *a* in the former structure, are buried vertically in beton in the foundation and consolidated by anchoring-stays *w*. There are then applied between the girders *v* the casing-planks for the formation of the beton, instead of its being necessary, as is usually the case, a complete mold extending from the wall that is to be raised to the center of the apparatus and completely filling the reservoir-space, the mold for the circular part being composed in the most cheap and simple manner by the vertical girders *v* and the planks which connect them. The sets of supports *v* buried in the beton being externally buttressed by the stays of the supports *w*, and the beton panels possessing, as above, the same system of metal strengthening helical bars *x*, single or double, arranged horizontally in the beton and continuously connected together, as in the case of the floor, it results that the thickness of the panels or circular wall can be considerably reduced while still maintaining a structure as solid as the ordinary heavy structures. As has

been already stated, this arrangement is therefore the same as the former, except that the structure is vertical instead of horizontal.

The process can likewise be applied to the 5 construction of quay-walls of less thickness than that usually adopted, while possessing the same stability, and generally to all structures.

Obviously the system is capable of numerous practical modifications while still remaining within the scope of the present invention. Thus without confining myself to details of the construction

I claim—

15 A new system of construction with beton strengthened by metal comprising the combi-

nation of a set of girders arranged in pairs with a space between the members of each pair and quite buried in a block of beton, of intermediate panels of beton, and of metal 20 strengtheners of helically-twisted iron bars passing through between the girders and through said panels and bent back upon themselves in the form of loops, the loops of one panel being engaged by the loops of the 25 adjacent panel, substantially as described.

In witness whereof I have hereunto set my hand in presence of two witnesses.

HEINRICH HENKEL.
